UNITED STATES PATENT OFFICE.

HENRY C. HINE, OF NEW BRITAIN, CONNECTICUT.

SUSPENDERS.

SPECIFICATION forming part of Letters Patent No. 728,712, dated May 19, 1903.

Application filed October 17, 1902. Serial No. 127,678. (No model.)

To all whom it may concern:

Be it known that I, HENRY C. HINE, a citizen of the United States, residing in New Britain, in the county of Hartford and State of Connecticut, have invented certain new and useful Improvements in Suspenders, of which the following is a specification.

This invention relates to suspenders and other garment-supporters, particularly those of the class illustrated in the patents granted to me September 9, 1902, No. 708,963, and October 14, 1902, No. 711,313; and its object is to simplify and improve the lever and hanger construction, especially with a view to reducing the number of the balls.

My invention may also be applied to other parts of suspenders or to other garment-supporters.

In the drawings forming part of this specification, Figure 1 represents a pair of suspenders embodying my improved trimming. Fig. 2 is a perspective view, partly broken away, of a lever-jointed to a hanger. Fig. 3 is an elevation of the lever and hanger, one of the plates of the former being removed. Fig. 4 illustrates the hanger. Fig. 5 is a sectional view illustrating the relation of the hanger and lever-plates, showing particularly how the latter are rigidly secured together, while leaving the lever free to vibrate; and Fig. 6 is a view similar to Fig. 5, but illustrating a modification of the central fastener.

Similar signs indicate similar parts throughout the drawings.

Shoulder-straps C and C' are attached, by means of chapes or connectors c and c', to the ends of a lever A, which at its middle portion is pivoted to a hanger B, the latter having an elongated eye b for the reception of tabs or suspender-ends D, although the parts C, C', and D may be otherwise connected to the lever and hanger. The lever A consists of a pair of oppositely-arranged plates a and a', preferably connected at their ends by rivets 2, whereon the chapes c and c' are pivoted. The lever-plates are formed with opposite struck-up annular grooves a³ and a⁴, suitable for receiving bearing-balls 4. The hanger B preferably consists of a single plate inserted between the lever-plates and is formed with a series of closed curved slots b³, which are disposed in a circle and are coincident

with the grooves a³ and a⁴ in the lever-plates. In each of said slots b³ is placed one of the balls 4, so that the hanger is supported by the balls. It will be understood that the walls or portions of the hanger between said slots at b' are within the ball-race, and hence prevent the balls from running together. These portions b' therefore form ball-separators, permitting a reduction in the number of balls requisite for supporting the hanger. It will be understood, however, that by using closed slots an important advantage is gained, since the portions of the plate at b' between the ends of the slots form ball-separators. The device at Fig. 4 may be regarded as having an annular space which is divided by a series of interruptions b' into the series of closed slots b³. It will be understood that the circular sides or treads of the slots are all concentric, this feature of construction being unaffected by the presence of the interruptions. Thus it will be seen that this portion of the invention comprises a shoulder-strap lever and a hanger for attachment to a suspender-end, that one of said elements A consists of a pair of plates and the other thereof, B, is inserted between said plates and has curved ball-engaging means formed therein, said curved ball-engaging means in this instance consisting of all of the outer or all of the inner sides or treads b⁴ of the slots b³ taken together, that at least one of said plates has a circular channel a³ or a⁴ coöperating with said curved ball-engaging means to form a ball-race, and that one of said race-forming elements is formed with interruptions (in this instance b') for maintaining separation of the ball. It will be understood that the presence of the interruptions b' does not interfere with the ordinary coöperation of the balls either with the grooves in the lever or with the corresponding curved edge or tread in the hanger. The hanger may be regarded as having a single annular slot having outer and inner circular bearing surfaces or edges, which form treads that work upon the balls, these edges, however, being formed with the interruptions b'. Notwithstanding these interruptions the balls ordinarily coöperate with one another and with the grooves and curved edges the same as if said interruptions were not existing. So far

as the ordinary operation of the balls are concerned these interruptions may therefore be disregarded, one of their principal purposes being to occupy portions of the ball-race, so 5 as to permit a reduction in the number of balls.

My invention further includes improved means for connecting the lever-plates a and a' so as to prevent lateral displacement of 10 either thereof or to prevent either from moving toward or away from the other. For this purpose I use a transverse fastener consisting in this instance of double-headed rivet 5, comprising a body portion 5^a, having double shoulders 15 5^b, against which the plates a and a' abut. The two heads 5^a of said rivet bind said plates to said shoulders, so that the plates are immovable with relation to each other in either inward or outward direction. By this 20 means the degree of separation of the plates may be accurately gaged, so that the parts may be made in large quantities and assembled without liability of inaccurate fitting of the balls in the races. The hanger B is provided with a central perforation 25 b² of sufficient size to clear the body of said rivet 5, as seen in Fig. 3. It will be seen that one of the plates is confined between one rivet-head and the body of the fastener at one end of 30 the latter, while the other of said plates is likewise confined at the other end of the fastener.

In the form of fastener illustrated at Fig. 6 a plain rivet 7 connects the lever-plates, the 35 heads of said rivets binding the plates against a collar 7^a, which is inserted between the plates and which corresponds to the body portion 5^a, the effect being the same as at Fig. 5.

The improved central fastening may be used 40 in connection with different kinds of ball-bearing suspender-trimmings. It will be seen that the central fastening device comprises an enlarged body between the plates and has at each end a head which rivets the plates to 45 said body.

It will be seen at Fig. 3 that not only is the use of a few balls permitted, but that a further 50 advantage is gained in that these balls may be distributed at substantially equidistant points, thereby to equalize the distribution of the stresses upon the parts, thus giving the maximum strength with the least expenditure for construction. This feature is of great advantage, especially in view of the extreme 55 thinness of the metal used for suspender-trimmings.

Having thus described my invention, I claim—

1. The combination of a shoulder-strap lever and a hanger for attachment to a suspender-end; said lever and hanger elements being formed of sheet metal; one of said elements consisting of a pair of plates and the other thereof being inserted between said 60 plates and having curved ball-engaging means formed therein; at least one of said plates having a circular channel coöperating with said 65

ball-engaging means to form a ball-race; and a set of balls in said race; one of said race-forming elements being formed with means 70 for maintaining separation of the balls.

2. The combination of a shoulder-strap lever and a hanger for attachment to a suspender-end; said lever and hanger elements being formed of sheet metal; one of said elements consisting of a pair of plates and the other thereof being inserted between said plates and having curved ball-engaging means formed therein; at least one of said plates having a circular channel coöperating with 80 said ball-engaging means to form a ball-race; and a set of balls in said race; said curved ball-engaging means being provided with an interruption which occupies a portion of the ball-race, whereby separation of the balls is 85 maintained.

3. The combination of a shoulder-strap lever and a hanger for attachment to a suspender-end; said lever and hanger elements being formed of sheet metal; one of said elements consisting of a pair of plates and the other thereof being inserted between said plates and having curved ball-engaging means formed therein; each of said plates having a circular channel coöperating with said ball- 90 engaging means to form a ball-race; and a set of balls in said race; said curved ball-engaging means being provided with a plurality 95 of interruptions within the ball-race, whereby separation of the balls is maintained.

4. The combination of a shoulder-strap lever and a hanger for attachment to a suspender-end; said lever and hanger elements being formed of sheet metal; one of said elements consisting of a pair of plates and the other thereof being inserted between said plates; said pair of plates being provided with opposite coöperating annular grooves; and said inserted plate having formed therein a series of closed slots coincident with said 105 grooves; and a ball inserted in each of said slots and working in said grooves.

5. The combination of a shoulder-strap lever and a hanger, both provided with parts which coöperate to form a single ball-race, 115 and a single set of balls in said race; one of said lever and hanger elements being formed with ball-separators within said race.

6. The combination of a shoulder-strap lever and a hanger for attachment to a suspender-end; said lever and hanger elements being formed of sheet metal; said lever consisting of a pair of plates and said hanger being inserted between said plates and having curved ball-engaging means formed therein; 120 said lever-plates having a circular channel coöperating with said ball-engaging means to form a ball-race; and a set of balls in said race; said hanger being formed with a series 125 of interruptions for maintaining separation 130 of the balls.

7. The combination of a shoulder-strap lever and a hanger for attachment to a suspender-end; said lever and hanger elements

being formed of sheet metal; one of said elements consisting of a pair of plates and the other thereof being inserted between said plates and having curved ball-engaging means formed therein; at least one of said plates having a circular channel coöperating with said bearing-surface to form a ball-race; and a set of balls in said race; said curved ball-engaging means being provided with an interruption which occupies a portion of the ball-race, whereby separation of the balls is maintained; and a central device for securing said pair of plates together so that neither can move either toward or away from the other.

8. The combination of a shoulder-strap lever and a hanger for attachment to a suspender-end; said lever and hanger elements being formed of sheet metal; one of said elements consisting of a pair of plates and the other thereof being inserted between said plates and having curved ball-engaging means formed therein; each of said plates having a circular channel coöperating with said bearing-surface to form a ball-race; and a set of balls in said race; said curved ball-engaging means being provided with a plurality of interruptions within the ball-race, whereby separation of the balls is maintained; and means at the center of said pair of plates for preventing lateral displacement of either thereof relatively to the other in lateral direction; said means comprising a part between the plates and a transverse fastener which binds said plates against said part.

9. The combination of a shoulder-strap lever and a hanger for attachment to a suspender-end; said lever and hanger elements being formed of sheet metal; one of said elements consisting of a pair of plates and the other thereof being inserted between said plates; said pair of plates being provided with opposite coöperating annular grooves; and said inserted plate having formed therein a series of closed slots coincident with said grooves; and a ball inserted in each of said slots and working in said grooves; and means at the center of said pair of plates for preventing displacement of either thereof relatively to the other in lateral direction.

10. The combination of a shoulder-strap lever and a hanger for attachment to a suspender-end; said lever and hanger elements being formed of sheet metal; one of said elements consisting of a pair of plates and the other thereof being inserted between said plates and having curved ball-engaging means formed therein; at least one of said plates having a circular channel coöperating with said ball-engaging means to form a ball-race; and a set of balls in said race; one of said race-forming elements being formed with an interruption for maintaining separation of the balls; and a central fastening device having a body between said pair of plates and also having at each end a rivet-head; said heads riveting said plates to said body.

11. The combination of a shoulder-strap lever and a hanger for attachment to a suspender-end; said lever and hanger elements being formed of sheet metal; said lever consisting of a pair of plates and said hanger being inserted between said plates and having curved ball-engaging means formed therein; said plates having circular channels coöperating with said ball-engaging means to form a ball-race; a set of balls in said race; said lever being provided with a series of interruptions within the ball-race, whereby separation of the balls is maintained; and a central fastening device having a body between said pair of plates and also having at each end a rivet-head; said heads riveting said plates to said body.

12. The combination of a shoulder-strap lever and a hanger for attachment to a suspender-end; said lever and hanger elements being formed of sheet metal; said lever consisting of a pair of plates and said hanger being inserted between said plates; said pair of plates being provided with coöperating opposite annular grooves; and said lever having formed therein a series of closed slots coincident with said grooves; a ball inserted in each of said slots and working in said grooves; and means at the center of said pair of plates for preventing lateral displacement of either thereof relatively to the other in lateral direction.

13. The combination of a shoulder-strap lever and a hanger for attachment to a suspender-end; said lever and hanger elements being formed of sheet metal; one of said elements consisting of a pair of plates and the other thereof being inserted between said plates; a ball-race formed partly in said inserted plate and partly in said pair of plates; a set of balls in said race; and means at the center of said pair of plates for separating said plates so that they accurately fit the balls and preventing lateral displacement of either of said plates relatively to the other in either inward or outward direction.

14. The combination of a shoulder-strap lever and a hanger for attachment to a suspender-end; said lever and hanger elements being formed of sheet metal; one of said elements consisting of a pair of plates and the other thereof being inserted between said plates; a ball-race formed partly in said inserted plate and partly in said pair of plates; and a central fastening device having a body between said pair of plates and also having at each end a rivet-head; one of said plates being confined between one rivet-head and the body of the fastener at one end of the latter, and the other of said plates being confined between the other rivet-head and the body of the fastener at the other end of the latter; said body being of such length as to separate said plates so that they accurately fit the balls.

15. The combination of a shoulder-strap lever and a hanger for attachment to a sus-

pender-end; said lever and hanger elements being formed of sheet metal; one of said elements consisting of a pair of plates and the other thereof being inserted between said 5 plates; a ball-race formed partly in said inserted plate and partly in said pair of plates; a set of balls in said race; and means at the center of said pair of plates for preventing lateral displacement of either thereof relatively to the other in either inward or outward direction; said means comprising a part

between the plates and a transverse fastener which binds said plates against said part; the latter being of a length to cause said plates to accurately fit the balls.

In testimony whereof I have hereunto signed my name at Nos. 9 to 15 Murray street, New York, N. Y.

HENRY C. HINE.
